(57) **CLAIM**

The ornamental design for a blade and blade holder, as shown and described.

DESCRIPTION

FIG. 1 is a perspective view of a first embodiment of a blade and blade holder showing our new design;

FIG. 2 is another perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a front elevational view thereof;

FIG. 9 is a right side elevational view of a second embodiment thereof; and,

FIG. 10 is a left side elevational view thereof.

The broken lines shown in the drawings illustrate portions of the blade and blade holder that form no part of the claimed design.
